UNITED STATES PATENT OFFICE.

CLARENCE W. COLEMAN, OF WESTFIELD, NEW JERSEY, ASSIGNOR, BY MESNE ASSIGNMENTS, TO HALL SWITCH & SIGNAL COMPANY, OF NEW YORK, N. Y., A CORPORATION OF MAINE.

RAILWAY SIGNALING SYSTEM.

1,174,229.

Specification of Letters Patent.

Patented Mar. 7, 1916.

Application filed May 7, 1909. Serial No. 494,665.

To all whom it may concern:

Be it known that I, CLARENCE W. COLEMAN, a citizen of the United States, and a resident of Westfield, Union county, New Jersey, have invented certain new and useful Improvements in Railway Signaling Systems, of which the following is a specification.

My invention relates to railway signaling systems of that type in which a pulsating or alternating current is used for controlling the signals.

The object of the invention is to provide a railway signaling system in which the signals are controlled by selective relays of the vibratory reed type.

My invention is shown in connection with an alternating current signaling system for electric traction roads, the system being of that type in which the rails are electrically continuous, with the block limits determined by cross bonds of negligible impedance between the rails. While I have shown my invention as applied to this system, it is obvious that it may be used in connection with other types of alternating current signaling systems than those using negligible impedance cross bonds. One of the chief problems to be overcome in signaling systems of this kind is the leakage of stray currents into the signaling circuits from other sources of current connected with the traction system; which currents interfere with, and cause the improper operation of the signals. In signals of this kind, when a signaling current of a certain character is used, it is necessary to provide a relay so arranged that it will respond only to the signaling current; and in certain other alternating current signaling systems, in which two or more currents differing in character are connected to a track with which the relays are operatively connected, it is necessary to provide selective relays, each of which will only be responsive to the current by which it is intended to be operated. For use in both of these systems, it has been proposed to utilize the well known motor types of relay, each having a coil on one member connected to the track and a coil on the other member connected to the signaling source intended to control the relay; but such relays are not only expensive to construct, but have two coils which are subject to the leakage of foreign currents.

In railway block signaling systems, the blocks are usually of considerable length, and since the signaling circuit along the rails of the block is twice the length of the block, the impedance of the iron rails, which increases with the frequency of the alternating signaling current, is so high that it requires a relatively high voltage across the rails, which is very detrimental, due to the loss of current from leakage, etc. It is necessary to have the propulsion current and the signaling current of different frequencies so that they will not interfere one with the other; but it is desirable to have only such difference between the frequencies as will insure the non-interference of the two currents, and any increase in the frequency of the signaling current above this point results in a great loss in the efficiency of the system. Prior to my invention as set forth in the appended claims herein, it was impossible to provide railway signaling systems embodying selective vibratory relays unless signaling currents were employed of a higher frequency than is necessary to insure the non-interference of the propulsion current with the signaling system; but by my invention, I am enabled to utilize a signaling current of much lower frequency without danger of the relay contacts being momentarily opened between current pulsations, which would result in a momentary false signal.

My invention involves the provision of a relay so constructed that it will be actuated to maintain its circuit closed when, and only when, the current in its coil is of a definite frequency. The relay may have but a single winding which may be connected directly across the track or to the secondary of a relay transformer, but in either case the selective action is not dependent upon any apparatus external to the relay itself. Specifically I provide as the armature of the relay a vibratory permanently magnetized reed which will be caused to vibrate by the field-magnet of the relay only when the field is energized by a current of a frequency corresponding substantially to the natural period of vibration of the reed, and I cause the continued vibration of the reed to maintain the closure of a circuit which is independent of the reed. This is effected by causing the contact actuated by the reed to be sluggish in its movement, as by being connected to a dash-pot. Thus I obtain the selective action of such a vibratory reed armature without

the intermittent closure of any circuit with the obvious disadvantages accompanying the same.

The invention will best be understood by 5 the following description, taken in connection with the accompanying drawings, in which—

Figure 1 is a side elevation of my preferred form of the relay. Fig. 2 is a plan view of the same. Fig. 3 is a side elevation 10 of a modification. Fig. 4 is a plan view of the same; and Fig. 5 shows diagrammatically a signaling system embodying my invention.

Referring to the drawings, Fig. 1, 1 is a 15 relay coil having a soft iron core 2, preferably secured to one end of a base plate 3, in the form of a permanent magnet which is provided with standards 4 and 5 at each end forming part of the magnetic circuit. Upon 20 the standard 4 is secured a projection 6, having a bifurcated vertical shoulder 7 provided with a longitudinally adjustable screw 8, adjusted by means of a nut 9. A vibratory armature 10, in the form of a steel reed, completes the magnetic circuit and is 25 detachably secured at its rear end to the screw 8, so that the armature may be moved back and forth over the core of the magnet by 30 manipulating nut 9.

The standard 4 preferably has its top 35 surface cored out, as shown, to provide shoulders 11 and 12, upon which the armature 10 rests. The upper surface of these shoulders should be substantially in the same horizontal plane with the center of the screw 8, so that the armature will rest easily upon both. The standard 4 is provided with the cored out cap plate 13, having offset shoulders 40 registering with the shoulders 12 and 13 for firmly gripping the armature 10 down on the standard, so that the vibration of the armature will take place from the outer end of shoulder 11.

A switch 14 preferably formed of resilient 45 metal and having arms 15 and 16, is mounted upon the standard 5 so as to engage an adjustable contact 18, which is mounted in a block of insulating material secured to a vertical extension of the standard. The 50 switch 14 and arms 15 and 16 are also secured to a block of insulating material, which is provided with a pivot pin journaled in the cupped ends of two adjustable screws, as shown.

The extremity of arm 15 is preferably 55 provided with a tip to receive the impulses from armature 10, while the outer end of arm 16 is pivotally connected with one element of a dash-pot 17, the other element of 60 which is secured to a projection from the base-plate. The dash-pot is filled with a liquid, preferably alcohol, and is for the purpose of retarding the movements of switch 14, so that its movements will be too 65 sluggish to allow it to make and break con-

tact in unison with armature 10, as a result of which the switch will be held in engagement with contact 18 during the vibrations of armature 10. After the armature has been adjusted by the nut 9 to its supposed proper length, it is gripped tightly upon the shoulders 12 and 13 by screwing down the cap plate, and the coil 1 is energized. If the natural period of vibration of the armature, as adjusted, is in resonance with the period of magnetic vibration set up in the coil, that is, if the natural number of vibrations per unit of time of the armature be the same as the number of cycles per unit of time of the current in the coil, then the armature will respond to the so-called magnetic vibrations set up by the coil, and will vibrate back and forth in unison with the reversals of current in the coil, thus giving a continuous rain of hammer blows upon the end of lever 15, forcing the switch 14 in engagement with contact 18 to close the signal circuit. The switch is held in its closed position by the dash-pot 17, which checks the vibrations of the switch member so as to prevent any possibility of the switch vibrating in unison with the armature 10.

If the length of the armature is such that its own period of vibration is substantially different from the magnetic vibration set up in the coil, then the armature will be unable to vibrate with sufficient amplitude to impinge upon the end of lever 15 to close the signal circuit, in which case the cap plate 13 is loosened up and the armature readjusted; after which the cap plate is again tightened up, and so on until the proper adjustment is secured.

In Fig. 3, I have shown a modified form of relay, in which two vibratory armatures 105 are utilized for operating the switch 14, one being mounted at each end of the permanently magnetized base-plate. These vibratory armatures being secured to opposite poles of the permanent magnet, are oppositely polarized, that is, the north pole of one and the south pole of the other are situated over the relay core, so that for each complete magnetic cycle in the core, the switch 14 will receive two blows, one from 110 each armature, while with the single vibratory armature the switch receives but one blow for each magnetic cycle in the core. The operation and adjustment of this relay is the same as that shown in Fig. 3, the only 115 difference in the relays being in the relative position of the parts to accommodate the second vibratory armature.

The standards 4 for carrying the vibratory arms, as shown in Fig. 3, are mounted 125 at the ends of the permanently magnetized base-plate, and secured to the same plate adjacent to one of the standards is an upright 19, upon which is pivoted the switch 14, and at the upper end of which is secured the in- 130

sulated contact 18. A second upright 20 is secured to the base-plate adjacent to the other standard and its upper end carries one member of the dash-pot 17. In this relay 5 it will be seen that the core 2 is mounted at the center of the permanent magnet and that the standards 4, uprights 19, operating lever 15 and vibrating armatures, complete the magnetic circuit.

10 One advantage of the two oppositely polarized vibrating armatures over the single armature is that the period between blows upon switch 14 is reduced by half, since the blows are alternately struck by the 15 two armatures, giving a more continuous action and thus preventing switch 14 from vibrating with either of them to make and break its circuit.

Another advantage in the use of two 20 armatures is that the switch will be held closed by the vibrations of one, should the other become broken or otherwise thrown out of order.

In Fig. 5 I have shown the relay as applied to a signaling system, in which 21 represents a track with electrically continuous rails, the block limits of which are determined by the cross bonds 22. Each block is supplied with alternating current by 25 means of a transformer 23, the secondaries of which are connected across the rails; and at the extremities of each block there is provided a coil 24 in inductive relation to the track circuit for supplying current to the 30 relay 1. At the entrance of each block is a signal 25, having its operating motor in a local block circuit, which is provided at each 35 end of the block with one of the relay operated switches 14.

40 The operation of the system, as shown, is as follows: When the block is empty, each track circuit, including the block rails and two adjacent cross bonds, is normally energized through its transformer 23, which 45 circuit supplies an alternating current to the relay 1 of the same frequency which is supplied by the transformer to the track circuit. The armatures 10 of each relay being adjusted to vibrate in synchronism with the 50 vibrations set up in the relay coil, the switches 14 at the ends of the respective local circuits will be held closed as long as the blocks are empty, and the signals will be held at safety. When a car enters a block 55 (say at B), the cross bond and rails at the entrance of the block are shunted out of the track circuit by the car axles, so that relay 1, at the entrance of the block, is deenergized, allowing switch 14 to open, thus de- 60 energizing the circuit 26 and allowing signal 25 to gravitate to danger. At some point after the car passes out of the first half of the block, and to the right of transformer 23, the track circuit, including the 65 rails and cross bond of the first half of the

block, will again be energized, supplying current to relay 1, causing the armature to vibrate and close switch 14 at the entering end of the block; but before that point is reached relay 1 at the exit end will be de- 70 energized, opening its switch 14, so that the signal 25 will remain at danger until the rear truck of the car has passed out of the block and beyond the cross bond at the exit end, when the relay at this end will also be 75 energized, closing circuit 26 to clear the signal 25.

It is obvious to those skilled in the art that various changes may be made in my invention without departing from the spirit 80 of the same, and all such changes are intended to be covered by the following claims.

What I claim as new and desire to secure by Letters Patent, is:—

1. In a railway signaling system, a circuit, a source of pulsating current supplying the same, a relay coil operatively related to said circuit, switch operating mechanism under the control of said coil constructed to respond only to a current in said coil of substantially the frequency of said source, and a switch actuated by said mechanism.

2. In a railway signaling system, a circuit, a source of pulsating current supplying the same, a relay coil operatively related to 95 said circuit, an armature adjacent to said coil, and a relay switch actuated by said armature, said armature and switch being constructed to operatively respond only to current in said coil of a substantially pre- 100 determined frequency.

3. In a railway signaling system, a track circuit, a source of pulsating current supplying the same, a relay coil operatively related to said track circuit, an armature adjacent to said coil constructed to be operatively actuated only by a current in said coil of substantially the frequency of said source, and a relay switch mechanically operated by said armature.

4. In a railway signaling system, a track circuit, a source of pulsating current supplying the same, a relay coil operatively related to said track circuit, a polarized armature adjacent to said coil constructed to be 115 vibratory in synchronism with the current of said coil, and a relay switch actuated by the vibrations of said armature.

5. In a railway signaling system, the combination of a circuit, a switch member for 120 controlling said circuit, a source of pulsating current, a relay coil operatively related to the same, and switch operating mechanism for moving the switch member by the force of a series of impulses and constructed to effectively actuate said switch only in response to a current in said coil of a substantially predetermined frequency.

6. In a railway signaling system, the combination of a source of pulsating current, a 130

4 relay coil operatively related to the same, means constructed to respond only to a current in said coil of a substantially predetermined frequency, and a switch member operated by the force of a series of impulses from said means and constructed to remain in a definite position during such impulses.

5 7. In a railway signaling system, a circuit, a source of pulsating current supplying the same, a relay coil operatively related to said circuit, a core for said coil, a permanent magnet, and switch operating mechanism secured to said magnet and operatively related to said core, constructed to respond only to a current in said coil of substantially the frequency of said source.

10 8. In a railway signaling system, the combination of a circuit, a switch member for controlling said circuit, a source of pulsating current, a relay coil operatively related to the same, and switch operating mechanism acting upon said switch and constructed to effectually actuate said switch member only in response to a current in said coil of a substantially predetermined frequency.

15 9. In a railway signaling system, the combination of a circuit, a switch member for controlling said circuit, a source of pulsating current, a relay coil operatively related to the same, and a polarized vibrating armature for said coil co-operatively related to said switch member to operate the same by a series of blows and constructed to operatively respond only to a current in said coil of a substantially predetermined frequency.

20 10. In a railway signaling system, the combination of a circuit, a switch member for controlling said circuit, a source of pulsating current, a relay coil operatively related to the same, and a polarized vibrating armature for said coil co-operating with said switch member and having a period of vibration substantially the same as the magnetic vibration set up by the coil and substantially different from the period of vibration of said switch member.

25 11. In a railway signaling system, a circuit, a source of pulsating current supplying the same, a relay coil operatively related to said circuit, relay switch mechanism under the control of said coil and constructed to respond only to a current in said coil of substantially the frequency of said source, a switch positively operated by said mechanism, and means for adjusting said switch mechanism.

30 12. In a railway signaling system, track circuits, sources of pulsating current supplying the same, signals and actuating mechanisms therefor, local circuits controlling said actuating mechanisms, electromagnetic switches in said circuits, each comprising a switch actuating coil operatively related to a track circuit, and switch mechanism adja-

35 cent to said coil constructed to respond only to a current in said coil of substantially the frequency of said sources.

40 13. In a railway signaling system, track circuits, sources of pulsating current supplying the same, signals and actuating mechanisms therefor, local circuits controlling said actuating mechanisms, electromagnetic switches in said circuits each comprising a coil operatively related to a track circuit, an armature adjacent to said coil, and a relay switch mechanically operated by means of said armature, said armature and switch being constructed to operatively respond only to a current in said coil of a substantially predetermined frequency.

45 14. In a railway signaling system, track circuits, sources of pulsating current supplying the same, signals and actuating mechanisms therefor, local circuits controlling said actuating mechanisms, electromagnetic switches in said circuits each comprising a coil operatively related to a track circuit, a vibratory polarized armature adjacent to said coil, and a switch actuated by the vibrations of said armature.

50 15. In a railway signaling system, track circuits, sources of pulsating current supplying the same, signals and actuating mechanisms therefor, local circuits controlling said actuating mechanisms, electromagnetic switches in said circuits each comprising a coil operatively related to a track circuit, a polarized armature constructed to be vibratory in synchronism with the current of said source and adjacent to said coil, and a switch actuated by the vibrations of said armature.

55 16. In a railway signaling system, a track circuit, a source of pulsating current supplying the same, a relay coil operatively related to the track circuit, a vibratory armature adjacent to said coil and a relay switch adjacent to said armature and adapted to be actuated by the movements of the armature but having a different character of movement, said armature being constructed and arranged to be effectively moved responsive only to currents in said coil of substantially the frequency of the current of said source.

60 17. In a railway signaling system, a track circuit, a source of pulsating current supplying the same, a relay coil operatively related to the track circuit, a vibratory polarized armature adjacent to said coil and an independently mounted relay switch member adjacent to said armature.

65 18. In a railway signaling system, a track circuit, a source of pulsating current supplying the same, a relay coil operatively related to the track circuit, a polarized armature having a free vibration substantially in synchronism with the current of said source and an independently mounted relay switch member adjacent to said armature.

19. In a railway signaling system, a track circuit, a source of pulsating current supplying the same, a relay coil operatively related to the track circuit, a polarized armature having a free vibration substantially in synchronism with the current of said source, a relay switch member adapted to be moved by the vibration of said armature, and means for dampening the movement of said switch member. 60
- 5 20. In a railway signaling system, a track circuit, a source of pulsating current supplying the same, a relay coil operatively related to the track circuit, a polarized armature having a free vibration substantially in synchronism with the current of said source, a relay switch member in the line of movement of said armature and a dash-pot for holding said switch member in a definite position while said coil is energized. 65
- 15 21. In a railway signaling system, the combination of a source of pulsating current, a relay coil co-operatively related to the same, and a plurality of oppositely polarized vibrating armatures for said coil constructed to operatively respond only to a current in said coil of a substantially predetermined frequency, and a switch controlled by said armatures. 70
- 25 22. In a railway signaling system, the combination of a source of pulsating current, a relay coil co-operatively related to the same, and a plurality of oppositely polarized vibrating armatures for said coil constructed to operatively respond only to a current in said coil of a substantially predetermined frequency, and a switch member mechanically operated by the vibrations of said armatures. 75
- 30 23. In a railway signaling system, the combination of a source of pulsating current, a relay coil co-operatively related to the same, and a plurality of oppositely polarized vibrating armatures for said coil constructed to operatively respond only to a current in said coil of a substantially predetermined frequency, and a switch member adjacent said armatures arranged to be moved to a given position and there maintained by the force of a series of impulses from said armatures. 80
- 35 24. In a railway signaling system, the combination of a circuit, a source of pulsating current, a relay coil connected to the same, a switch member having a comparatively slow period of vibration, a polarized vibrating armature for said coil co-operatively related to said switch member and having a substantially different period of 85
- 40 vibration from said member, and means for varying the period of vibration of said armature. 90
- 45 25. In a railway signaling system, the combination of a circuit, a source of pulsating current, a relay coil operatively related to said source, a contact member in said circuit mounted adjacent to said coil, a switch member co-operating with the same, a retarding device for said switch member, a polarized vibrating armature adjacent 95
- 50 said coil, means for supporting the armature, means for varying the operative length of said armature, and means for clamping the armature to its support at a plurality of points along its length. 100
- 55 26. In a block signal system, a source of alternating current connected to the track rails, a track relay comprising a winding supplied with current from said source through the track rails and a vibrating polarized magnetic member disposed in the magnetic field produced by current in said winding and tuned to a natural period of vibration corresponding to the frequency of the current normally delivered by said source, and a signal controlled by the vibration of said member. 105
- 60 27. In a block signal system, a source of alternating current connected to the track rails, a track relay comprising a winding supplied with current from said source through the track rails and a vibrating polarized magnetic member disposed in the magnetic field produced by current in said winding and tuned to a natural period of vibration corresponding to the frequency of the current normally delivered by said source, contacts actuated by the vibration of said member, and a signal controlled by 110
- 65 said contacts. 95
- 70 28. In a block signal system, a source of alternating current connected to the track rails, a track relay comprising a winding supplied with current from said source through the track rails and a member adapted to be vibrated by an alternating current in said winding and tuned to a natural period of vibration corresponding to the frequency of the current normally delivered by said source, and a signal controlled by the vibration of said member. 100
- 75 In testimony whereof, I have signed my name to this specification, in the presence of two subscribing witnesses.
